UNITED STATES PATENT OFFICE.

HJALMER C. GUSTAFSON, OF DENVER, COLORADO, ASSIGNOR TO THE DENVER ROCK DRILL MANUFACTURING COMPANY, OF DENVER, COLORADO, A CORPORATION OF DELAWARE.

TOOL-RETAINER.

1,207,901.

Specification of Letters Patent. Patented Dec. 12, 1916.

Application filed August 29, 1916. Serial No. 117,455.

To all whom it may concern:

Be it known that I, HJALMER C. GUSTAFSON, a citizen of the United States, residing at Denver, in the county of Denver and State of Colorado, have invented certain new and useful Improvements in Tool-Retainers, of which the following is a specification.

The present invention relates to tool-retaining means, and while particularly intended for retaining drill bits in the sockets of the tools that operate on said bits, is not necessarily limited thereto.

One of the primary objects of the present invention is to provide a relatively inexpensive structure which at the same time is thoroughly practical and is not liable to become deranged through long continued use or through the carelessness of the workmen, the mechanism being such that the apparatus may be held either with the retainer in its operative or inoperative position.

In the embodiment disclosed—Figure 1 is a plan view of one embodiment of the invention, Fig. 2 is a front elevation of the same. Fig. 3 is a side elevation. Fig. 4 is a detail longitudinal sectional view on the line 4—4 of Fig. 1. Fig. 5 is a cross sectional view on the line 5—5 of Fig. 1. Fig. 6 is a view similar to Fig. 3, but showing the device in its inoperative position. Fig. 7 is a detail sectional view of a slightly modified form of construction.

Similar reference numerals designate corresponding parts in all the figures of the drawings.

In the embodiment illustrated, a tool holding member 8 is disclosed, which may be the head of a well known form of hammer drill, said head having a socket to loosely receive the end of a tool or bit 9, which can be readily introduced or withdrawn therefrom, as is well understood to those skilled in the art, said tool having a flange or collar 10 thereon. The tool holding member 8 is provided with oppositely outstanding ears 11 through which are passed the side bolts 12 for securing the head or tool holding member 8 in place on the apparatus. Mounted on the front ends of the side bolts are heads 13 which are in the form of annular detachable nuts threaded to said bolts, as shown at 14, and having their front ends forked to

provide spaced ears 15. The usual springs 16 are interposed between the heads 13, and 55 the ears 11.

The tool retaining member is mounted on the side bolts, and includes a yoke 17 arranged to embrace the tool 9 in advance of the collar 10, said collar being of sufficient 60 size to abut against the yoke upon the forward movement of the tool 9. The yoke is provided with rearwardly extending divergently arranged side elements 18 constituting sections of side arms that are slidable 65 upon other sections, said latter sections being in the form of eye bolts 19. The elements or sections 18 terminate in opposite eyes 20 slideable upon said bolts 19 and the rear ends of the elements 19 have eyes 21 70 which are located between the ears 15 and are pivotally connected thereto by transversely disposed pins 22. These eyes are extended and fit in rounded recesses 21^a formed in the rear ends of the eyes 20, the recesses 75 21^a being the same width as the eyes and thus preventing the turning of the eyes and consequently the turning of the heads 13. Upon the front ends of the bolts 19 are placed nuts 23 and washers 24. Coiled 80 springs 25 located on the bolts 19, bear against the eyes 20 and frictionally maintain said eyes against the front ends of the bolt heads 13. In order to secure the yoke 85 against accidental swinging movement when in its operative position, as shown in Fig. 3, the ears 15 of the bolt heads 13 are preferably provided with sockets 26 that receive lugs 27 formed on the eyes 20. With this construction, it will be noted that the yoke 90 is really provided with extensible side arms which are pivotally mounted upon the heads of the side bolts, and that the extension of these side arms is resisted by the springs 25.

It is believed that the manner of using 95 the device will be obvious. When the tool retaining member is swung to the position shown in Fig. 6, it is out of associated relation with the bit 9, and said bit can be withdrawn from the tool holding member 8 or 100 placed in position without interference. If, however, the tool retaining member is swung to the position shown in Fig. 3, the yoke being disposed in advance of the collar, said 105 collar will strike said yoke upon the forward movement of the tool, or reversely if the ap-

paratus is moved rearwardly, the yoke will engage the collar and consequently the tool will be retained in the tool holding member. 8. When the yoke is in its operative position, the lugs 27 thereof engaging in the sockets 26, will retain the same against accidental swinging movement, and the springs 25 will serve to afford a yielding resistance to the forward movement of the yoke under the impact of the collar of the tool striking the same.

A slight modification of the structure is shown in Fig. 7, wherein one of the side bolts is shown and designated 12^a. This 15 side bolt is provided with a head 13^a having spaced ears 15^a, the end and upper faces 26^a of said ears being flat and disposed in angular relation. The usual spring 16^a is interposed between the head 13^a and the drill 20 holding member, and an eye bolt 19^a is pivotally mounted between the ears 15^a by the transverse pin 22^a. The yoke 17^a has side elements 18^a terminating in eyes 20^a that are slidable on the bolts 19^a, and are yieldingly 25 held against the ears 15^a by springs 25^a. These eyes 20^a have flat rear faces and consequently will be seated either against the end or upper faces 26^a of the ears 15^a so that the yoke will be positively held in its operative or inoperative position.

Having thus fully described my invention, what I claim as new, and desire to secure by Letters Patent is:—

1. In apparatus of the character set forth, the combination with a tool holding member, of securing means therefor, a tool retaining device having a pivotal mounting on the securing means and capable of forward movement, and yielding means swinging with the device for resisting the forward movement.

2. In apparatus of the character set forth, the combination with a tool holding member, of side bolts for securing the same in place, 45 a swinging tool retaining device having a pivotal mounting on the side bolts and capable of forward movement under the impact of a tool striking the same, and yielding means swinging with the device for resisting its forward movement.

3. In apparatus of the character set forth, the combination with a tool holding member, of securing means therefor, and an extensible tool retaining member movably mounted on the securing means.

4. In apparatus of the character set forth, the combination with a tool holding member, of side bolts for securing the same in place, and a swinging tool retaining member comprising a yoke pivotally mounted on the side bolts and extensible longitudinally of the tool retained thereby.

5. In apparatus of the character set forth, the combination with a tool holding member, of side bolts for securing the same in

place, and a swinging tool retaining member comprising a yoke having yielding longitudinally extensible side arms pivotally mounted on the side bolts.

6. In apparatus of the character set forth, 70 the combination with a tool holding member, of a tool retaining member comprising eye bolts having a pivotal mounting, a tool engaged yoke having side elements slidably engaged with the eye bolts, and springs on 75 the eye bolts bearing against the elements to resist their sliding movements.

7. In apparatus of the character set forth, the combination with a tool holding member, of side bolts for securing the same in place, 80 said bolts having heads, and a tool retaining member pivoted to the heads of said bolts.

8. In apparatus of the character set forth, the combination with a tool holding member, of side bolts for securing the same in 85 place, said bolts having heads, eye bolts pivoted to the heads, a tool retaining yoke having side elements slidable on the eye bolts, and springs mounted on the eye bolts and bearing against the yoke.

9. In apparatus of the character set forth, the combination with a tool holding member, of means for yieldingly securing the same, a tool retaining device movably mounted on the securing means, and yielding 95 means for permitting the movement of the device on the impact of blows from the tool, said tool retaining means being also movable from and to a position to engage a tool, and said last mentioned yielding means moving therewith.

10. In apparatus of the character set forth, the combination with a tool holding member, of securing means therefor, a tool retaining device mounted on the securing 105 means to have a swinging movement, and springs located on opposite sides of the mounting.

11. In apparatus of the character set forth, the combination with a tool holding 110 member, of side bolts therefor having heads, springs interposed between the heads and tool holding member, a tool retaining yoke, means for pivotally mounting the yoke on the heads, and springs bearing against the 115 yoke to resist its forward movement.

12. In apparatus of the character set forth, the combination with a tool receiving member having outstanding ears, of side bolts passing through the ears and having 120 heads, springs interposed between the heads and ears, a tool retaining yoke, means for pivotally mounting the tool retaining yoke on the heads, and springs carried by said means and bearing against the yoke, for 125 resisting its forward movement.

13. In apparatus of the character set forth, the combination with a tool holding member, of a securing bolt therefor, and a tool retaining yoke having a pivotal mount- 130

ing on the bolt and also having a bearing at one side thereagainst to maintain said yoke in a predetermined position, and yielding means bearing against the opposite side ³ of the yoke for maintaining the bearing of said yoke against the bolt.

14. In apparatus of the character set forth, the combination with a tool holding member, of a securing bolt therefor having ¹⁰ a head, and a tool retaining yoke having a pivotal mounting on the bolt and also having a bearing on the head.

15. In apparatus of the character set forth, the combination with a tool holding member, of a securing bolt therefor having ¹⁵ a head, a swinging tool retaining yoke, a mounting for the yoke pivotally mounted on said head, and means for yieldingly maintaining the yoke in engagement with the head.

16. In apparatus of the character set forth, the combination with a tool holding member, of side bolts therefor having heads, a tool retaining yoke, devices for pivotally ²⁵ mounting the yoke on the heads, said yoke having frictional engagement with the head, and springs carried by the mountings and

bearing against the yoke to maintain such frictional engagement.

17. In apparatus of the character set forth, the combination with a tool holding member, of a tool retaining member including a pivoted bolt, a tool engaging yoke slideable on the bolt, and means causing an interlocking engagement between the yoke and ³⁵ bolt to prevent their relative rotation on the longitudinal axis of the bolt.

18. In apparatus of the character set forth, the combination with a tool-holding member, of a tool retaining member including a pivoted bolt having an eye, and a tool engaging yoke slideable on the bolt, said ⁴⁰ yoke having an opening through which the bolt passes and having a recess to receive the eye and prevent the relative rotation of the ⁴⁵ yoke and bolt on the longitudinal axis of the bolt.

In testimony whereof I affix my signature in the presence of two witnesses.

HJALMER C. GUSTAFSON.
